Des. 203,943
Patented Mar. 1, 1966

203,943

SERVING SPOON OR THE LIKE

Clayton A. Laughlin, Minneapolis, Minn., assignor to
Arthur Salm Inc., Chicago, Ill., a corporation of
Illinois

Filed Mar. 15, 1965, Ser. No. 84,257

Term of patent 14 years

(Cl. D44—29)

FIG. 1 is a perspective view of a serving spoon showing my new design;

FIG. 2 is a top plan view thereof;

FIG. 3 is a side elevational view thereof; and

FIG. 4 is a top plan view of another form of serving spoon embodying the new design wherein a group of slots is provided in the bowl portion as shown.

I claim:

The ornamental design for a serving spoon or the like, substantially as shown and described.
